UNITED STATES PATENT OFFICE

PAUL SCHONERT, OF NORTH LITTLE ROCK, ARKANSAS

ROOF CONSTRUCTION

Application filed October 15, 1929. Serial No. 399,766.

This invention relates to a roof construction and more particularly to a flashing block for use in connection therewith.

Heretofore, in certain types of roofs, it has been a difficult matter to prevent leakage under all conditions where the usual flashing is provided.

One of the objects of the present invention is to provide a novel form of flashing block which will hold not only the roof flashing but also a counter-flashing.

Another object is to provide a flashing block formed in a single piece which can be set up readily for engagement with both the flashing and the counter-flashing.

A further object is to combine with the flashing block a means for retaining asphalt or any other suitable binder used for causing the flashing to adhere to the block.

A still further object is to provide a flashing block so constructed as to permit insertion of a built-up roof without necessitating an abrupt bend of the roof surface.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing, which is a section through the flashing block and a portion of the roofing and adjacent structure, the preferred form of the invention has been shown.

Referring to the drawing by characters of reference, 1 designates a flashing block formed in a single piece of concrete or other suitable material and this block has an upper groove 2 extending longitudinally within one face thereof below which is arranged another longitudinal groove 3 preferably deeper and wider than the groove 2 and disposed at an acute angle to the adjacent face of the block. The block has its bottom portion extended outwardly beyond the grooved face of the block to provide an inclined sur-

face 4 which constitutes a continuation of the bottom of the slot 3. This surface is corrugated longitudinally of the block as indicated at 5 to provide longitudinal recesses or gutters in the extension 6 of the block 1.

In practice the blocks 1 are set up in their proper positions, each block being placed in one operation so that the laying of the blocks is greatly simplified as compared with those requiring the employment of two or more pieces to each complete flashing block. After the blocks have been set up and alined, pitch, tar, or other suitable binding material indicated at 7 is placed in the recesses or gutters 5 so as to form a coating for the inclined surface of the block, this coating material being extended upwardly into the groove 3. The marginal portion of a built-up roof indicated at R can then be inserted into the groove 3 and affixed to the inclined surface of extension 6 by means of the coating material 7.

After the built-up roof has been placed in position the counter-flashing, indicated at F, is inserted into the groove 2 and applied to that portion of the built-up roofing supported by the extension 6. Any spaces left in the grooves after the several parts have been assembled can be filled with roofing cement or other suitable material indicated generally at C.

By providing the corrugated surface the coating or binding material will be prevented from flowing downwardly to an objectionable extent if of a nature tending to flow when subjected to heat. The corrugations also serve as an added means for preventing moisture from working upwardly along the extension 6 of the flashing block.

What is claimed is:

1. A flashing block formed in a single piece of material having the bottom portion thereof extended well beyond one face of the block to provide an inclined surface for supporting the inclined marginal portion of a roofing material, there being a longitudinal groove extending into the block from said surface and having its bottom alining with and constituting a continuation of said inclined surface for supporting the edge of

100

said marginal portion, there being a series of transverse grooves in the inclined surface of the extension and in the alining wall of the groove in the block for retaining an adhesive applied to said surface and wall.

- 5 2. The combination with a flashing block formed in a single piece of material having an extension at the lower portion thereof projecting well beyond one face and super-
10 posed grooves in said face of the block, the bottom wall of one of the grooves constitut-
15 ing a continuation of one surface of the ex-
tension, there being longitudinal corruga-
tions formed by said surface and disposed in an inclined series, of a roofing material ex-
20 tending into one of the grooves, means retain-
ed by the corrugations for affixing a portion of said material to the extension, means for
filling the groove above the roofing material
therein to hold the affixing means against
25 release from the corrugations in said grooves,
and a counter-flashing seated in the other
groove and bearing upon that portion of
the roofing arranged on the extension.

25 In testimony that I claim the foregoing
as my own, I have hereto affixed my signa-
ture.

PAUL SCHONERT.
